UNITED STATES PATENT OFFICE.

CARL SCHALLER, OF BRUNSWICK, GERMANY, ASSIGNOR TO GRIMME, NATALIS & CO.,
COMMANDITGESELLSCHAFT AUF ACTIEN, OF BRUNSWICK, GERMANY, A CORPORATION
OF GERMANY.

COMPUTING-MACHINE.

1,220,008.

Specification of Letters Patent. Patented Mar. 26, 1917.

Application filed November 15, 1915. Serial No. 61,574.

To all whom it may concern:

Be it known that I, CARL SCHALLER, workmaster, a citizen of the Duchy of Brunswick, Empire of Germany, residing 5 at Brunswick, Germany, have invented certain new and useful Improvements in Computing-Machines, of which the following is a specification.

My invention relates to computing or 10 calculating machines. The object of my invention and the means by which I attain the object, will be more readily understood by reference to the accompanying drawing in which I have illustrated, in a sectional 15 side elevation, a machine of the type to which my invention is particularly applicable.

The illustrated computing machine is of 20 the type in which numbers and items can be set up by means of disks *e* revolvably mounted upon the shaft *k* and provided with the tongue-like handles *i*. The disks *e* have cam grooves *l* into which project lateral extensions *m* of the teeth *n* which are slidably 25 carried in disks *a* fixedly mounted upon the shaft *k*. When the handle *i* of any disk *e* is moved a certain extent a corresponding number of teeth *n* will be caused to move radially outward so as to project from the 30 circumference of the disk *a* which is associated with the disk *e* thus operated. When the main operating crank *o* is turned, the teeth *n* previously set up will then transmit to the counting mechanism *g* through the 35 intermediate wheel *p*, a movement corresponding in its extent to the numbers of teeth *n* moved outward and projecting from the disk *a*. Machines of this type are frequently furnished with an indicating mechanism or item register *g* on which the set 40 up numbers and items appear visible to the eye, the numbers and items being transferred to the indicating mechanism *g* from the cam disks *e* through intermediate 45 wheels *h*.

In machines of this type, the necessity of disconnecting the indicating mechanism or register after the numbers and items are set up by means of the handles *i* and previously 50 to the starting of the main operating lever *o*, if an alteration in the number set up in the register is to be prevented, constitutes a drawback.

It is the object of my invention to over-

come this drawback by providing a device 55 in which the actuating means for the indicating register is of such a character that during the rotation of the setting-up wheel *a* effected by the movement of the operating handle, no action is exerted upon said register, so that the number set up therein remains unchanged.

For this purpose the setting-up wheel *a* which carries the slideable teeth *n* but is stationary while the teeth are being set up, is 65 provided with an actuating member *c*, *d*, which receives its motion from the cam disk *e* and transmits the received motion to the register *g*, either directly or through an intermediate operating member, as shown 70 in the construction illustrated. As a result of this arrangement, the actuating member *c*, *d*, performs an actuating movement only when the setting-up wheel on which said actuating member is revolvably mounted, is 75 stationary and the cam disk *e* is moving relatively thereto; but the actuating member *c*, *d*, does not transmit any motion to the indicator *g* when the setting-up wheel *a* and the cam disk *e* which otherwise produces the actuating movement, are both 80 revolving simultaneously and in the same direction.

In the construction illustrated, the setting-up wheel *a* carrying the adjustable 85 teeth *n*, is provided with a pivot *b* on which the actuating member is rotatably mounted, this actuating member being here shown as comprising a star wheel *c*, having rigidly connected thereto, a toothed gear wheel *d* 90 which meshes with the internal gear teeth *f* of the cam disk *e*. The disposition of the star wheel is such that the same advances the intermediate wheel *h* operating the indicating mechanism or register *g* when the cam 95 disk *e* is rotating the star wheel *c* by means of the curved rack formed by the teeth *f* and the pinion *d*. But this independent rotation of the star wheel will take place only when the setting-up wheel *a* is stationary, 100 and the cam-disk *e* is rotating relatively thereto. The teeth of the star wheel *c* are always out of engagement with the teeth of the intermediate wheel *h* when the cam disk is in the position corresponding to 105 zero or to any other of those figures or digits that can be set up by means of the cam disk *e*. From this it follows that the

intermediate wheel h will not be advanced when the setting-up wheel a is revolving, since the setting-up wheel a is not revolved until after the cam disk e has been adjusted 5 to set up a certain number, and then only upon actuation of the main crank or handle o , at which time it revolves simultaneously with the setting-up wheel a . In moving the cam disk e , the spring-controlled detent v of well known construction and fixedly 10 mounted upon the shaft h , operates to prevent the cam disk from assuming any intermediate position.

To prevent any accidental rotation and 15 to limit the extent of each advance of the indicating mechanism, yielding stopping devices may be provided. As an example, I have illustrated in the drawing a detent r mounted on a stationary pin s and subjected to the action of a spring t which tends 20 to press the head of the detent r between the teeth of the intermediate wheel h .

It is obvious that the scope and applicability of my invention is not restricted to 25 the particular devices and means shown and described hereinbefore by way of example, but that the latter may be varied within wide limits without involving a departure from the spirit of my invention.

30 What I claim and desire to secure by Letters Patent of the United States, is:

1. In a computing machine, the combination, with indicating mechanism; of setting mechanism, comprising a movable setting member, and a member for positioning said setting member movable both relatively to and in unison with the same; and a device for transmitting the movements of said setting mechanism to said indicating mechanism; said device actuated by said positioning member during its movement relative to said setting member, but inactive during the movement of the latter and the positioning member in unison.

45 2. In a computing machine, the combination, with indicating mechanism; of setting mechanism, comprising a movable setting member, and a member for positioning said setting member disposed in juxtaposition thereto and movable both relatively to and in unison with the same; and a device for transmitting the movements of said setting mechanism to said indicating mechanism; said device movably mounted on said setting 50 member and adapted to be engaged and actuated by said positioning member during its movement relative to said setting member, but inactive during the movement of the latter and the positioning member in unison.

55 3. In a computing machine, the combination, with indicating mechanism; of setting mechanism, comprising co-acting, juxtaposed setting and positioning disks, the positioning disk being rotatable both relatively 60 to and in unison with the setting disk; and

a device for transmitting the movements of said setting mechanism to said indicating mechanism; said device rotatably mounted on the setting disk and adapted to be driven by the positioning disk during its rotation relative to said setting disk, but inactive during the rotation of the latter and the positioning disk in unison. 70

4. In a computing machine, the combination, with indicating mechanism; of setting mechanism, comprising a movable setting member, and a member for positioning said setting member disposed in juxtaposition thereto and movable both relatively to and in unison with the same; and a device for 80 transmitting the movements of said setting mechanism to said indicating mechanism; said device movably mounted on said setting member and comprising a pair of rigidly-connected parts, one adapted to engage 85 and drive said indicating mechanism, and the other adapted to be engaged and driven by said positioning member during its movement relative to said setting member, but inactive during the movement of the latter 90 and the positioning member in unison.

5. In a computing machine, the combination, with indicating mechanism; of setting mechanism comprising co-acting, juxtaposed setting and positioning disks, the positioning disk being rotatable both relatively to and in unison with the setting disk and being provided with a toothed portion; and a device for transmitting the movements of said setting mechanism to said indicating mechanism; said device rotatably mounted on the setting disk and comprising a pair of rigidly-connected parts, one adapted to engage and drive said indicating mechanism, and the other adapted to be engaged and 100 driven by the toothed portion of the positioning disk during its rotation relative to said setting disk, but inactive during the rotation of the latter and the positioning disk 105 in unison. 95

6. In a machine of the character described, the combination of: a revolute member, a second revolute member associated with said first member and adapted to revolve independently of said first member, a mechanism adapted to be actuated by said second member, and means for transmitting the actuating motion from said second member to said mechanism, said means being pivotally mounted on said first member and comprising 110 a pinion actuated from said second member and a part integral with said pinion and adapted to intermittently engage said mechanism when said second member is 115 moving independently of said first member. 120

7. In a computing machine, the combination of: a setting-up wheel, a cam disk associated with said setting-up wheel and adapted to revolve independently of and simultaneously with said setting-up wheel, an indi- 130

- cating mechanism adapted to be actuated from said cam disk, and an actuating member pivotally mounted on said setting-up wheel and comprising a pinion adapted to engage said cam disk and a star wheel fixedly connected with said pinion and adapted to advance said indicating mechanism when said pinion is being rotated by said cam disk.
- 10 8. In a computing machine, the combination of: a setting-up wheel, a cam disk associated with said setting-up wheel and adapted to revolve independently of said setting-up wheel, an indicating mechanism adapted to be actuated from said cam disk, an actuating member pivotally mounted on said setting-up wheel, said actuating member comprising a pinion adapted to engage said cam disk and an integral star wheel adapted to intermittently advance said indicating mechanism when said pinion is being rotated by said cam disk, and means adapted to prevent accidental movement of said indicating mechanism.
- 15 9. In a computing machine, the combination of: a setting-up wheel, a cam disk associated with said setting-up wheel and adapted to revolve independently of said setting-up wheel, an indicating mechanism adapted to be actuated from said cam disk, an actuating member pivotally mounted on said setting-up wheel, said actuating member comprising a pinion adapted to engage said cam disk and an integral star wheel adapted to intermittently advance said indicating mechanism when said pinion is being rotated by said cam disk, and means adapted to prevent accidental movement of said indicating mechanism.
- 20 10. In testimony whereof I have hereunto set my hand in presence of two subscribing witnesses.
- 25 11. C. A. SCHALLER.
